Patented July 2, 1963

195,603

DISPENSING CLOSURE

Arthur Wesley Newby, 1265 Schaumburg Road,
Elgin, Ill.

Filed May 8, 1961, Ser. No. 65,051

Term of patent 14 years

(Cl. D58—26)

Fig. 1

Fig. 2

Fig. 3

Fig. 4

Fig. 5

Fig. 6

FIG. 1 is a side elevational view of a dispensing closure showing my new design;

FIG. 2 is a front elevational view thereof;

FIG. 3 is a top plan view thereof;

FIG. 4 is a side elevational view thereof with the spout in dispensing position;

FIG. 5 is a front elevational view thereof; and

FIG. 6 is a top plan view thereof.

I claim:

The ornamental design for a dispensing closure, substantially as shown.
